ELECTRIC PLUG

Emanuel B. Barnitz, Johnstown, Pa.

Application July 22, 1936, Serial No. 92,037

6 Claims. (Cl. 200—51)

In electric plugs used on appliances, such as irons, the plug is frequently removed from the appliance while the switch is "on" and the circuit closed, thus setting up arcing in the plug. The present invention contemplates the use of a plug in which the switch is necessarily in an "off" position before the plug can be removed from the appliance.

This invention also includes a plug, capable of use with conventional irons and other appliances, and embodying a hand engaging portion to facilitate removal of the plug from the iron, said hand engaging portion constituting a switch whereby the initial outward movement thereof opens the circuit, continued movement disengaging the plug from the iron.

In the drawing:

Fig. 1 is a perspective view of a plug connector constructed in accordance with the present invention, showing a portion of an electric cord mounted therein.

Fig. 2 is a side elevational view looking at the inside of one part of the electric plug, and showing the plug mechanism and a portion of the electric cord mounted therein.

Fig. 3 is a longitudinal sectional view taken on the line 3—3 of Fig. 2 looking in the direction of the arrows.

Fig. 4 is a fragmentary elevational view of a modified form of plug showing the switch in an open position.

Fig. 5 is a fragmentary edge elevational view of the plug illustrated in Fig. 4 showing to advantage the means employed to hold the switch in an open position, and

Fig. 6 is a fragmentary elevational view of another modified form of plug showing the switch in an open position.

The plug of the present invention includes a body, consisting of two parts, 7 and 8, the latter being slidably mounted in the former. The plug proper 7, consists of two parts, each of which is suitably recessed to receive contacts 9, and the inner ends of the movable part 8. The part 8 is also composed of two elements between which an electric cord 10 is clamped.

By slidably mounting the part 8 in the body of the plug, the electric cord 10 can be urged into electrical engagement with the contacts 9 to close an electric circuit from the source of supply to an appliance in a manner well known in the art. The part 8, therefore, constitutes a switch which is normally open through the medium of springs 11, one end of each of which is embedded in one of the parts of the plug body

1, the opposite end of the spring projecting into one of the recesses of said body in engagement with the inner ends of the switch body 8. The springs 11 normally urge the part 8 outwardly, as shown in Figs. 2 and 3 of the drawing. However, manual pressure on the part 8 overcomes the resistance of the springs 11 and flexes them laterally into engagement with extensions 12, extending from the contacts 9. When in this position, the inner ends of the part 8 are in engagement with the reversely folded terminals 13 of extensions formed on the contacts 9.

Preferably, the strands of the cord 10 extend through the sides of the part 9 and are clamped into engagement with the latter by contact caps 14.

Each of the caps 14 is equipped with lateral flanges 15 which slide in complementary grooves formed in the side walls of the part 8. The caps may be easily and quickly removed when desired, or found necessary. The strands of the cord 10 are held completely separated by a partition 16 formed in the part 8, the partition having a longitudinal extending opening formed therein in which is adapted to slide ribs 17 formed on the parts of the main body of the plug 1.

The elements of the part 8 are held together by the caps 14 and a yieldable clamping ring 18 which is flexed over the top of said elements as illustrated to advantage in the drawing. If desired, however, a screw 19 may be engaged through said elements.

To facilitate disengagement of the plug from an iron, or other appliance, the part 8 is formed to provide finger engaging recesses 20. When it is desired to remove the plug, the fingers are engaged in said recesses in a manifest manner and pressure exerted thereon. If the switch is in a closed position, the first movement of the part 8 breaks the circuit. Continued movement disengages the plug from the appliance.

In Figs. 4 and 5 a slight modified form of the invention is illustrated. In this form, the springs 11 are eliminated. The contacts, indicated at 9', are provided with vertical extensions, the upper ends of which are bent over to provide resilient terminals 21. These terminals are adapted to engage contact caps 14' of the switch part 8' of the plug so as to establish an electric connection between the cord 10' of the switch part 8' and the contacts 9'. In this form of invention, the switch part 8' is normally held in an outward position by a resilient strap 22 mounted in the plug and engageable with notches 23 mounted in the side of the switch part 8'.

In the form of invention shown in Fig. 6 of the 55

drawing, the switch caps 14' are eliminated and in their stead contact screws 14² are employed, these being in electrical engagement with strands of the electric cord. The electric cord is carried by movable switch part 8², shown fragmentarily. 5 One of the screws 14² is normally in engagement with the upper end of a resilient strap 22', the latter being an extension of each of the contacts 9² of the plug. The strap 22' serves the dual purpose of a conductor for one side of the switch, between the electric cord 10' and the contacts 9² and in addition serves as a spring to normally hold the switch part 8' in an outward position as shown in the drawing. The other contact screw 14² is adapted to engage an extension 24 formed on the other contact 9² only after the switch part 8² has moved inwardly into the plug part. As 10 soon as said other contact 14² engages the extension 24, the circuit is closed between the electric 15 cord and the contacts.

Although I have herein shown three forms of my invention, I am nevertheless aware that various changes may be made within the scope of the present invention, as covered by the claims here- 20 inafter set forth.

What is claimed is:

1. A plug for electric appliances including a body having contacts for engagement with an electric appliance, a part of said body being equipped 30 with a cord and movable, when the body is in an operative position on an appliance, for placing the cord in electrical engagement with said contacts.
2. A plug for electric appliances including a 35 plug body, a part of which is movable, when the body is in an operative position on an appliance, contacts in the body proper and an electric cord in said movable part, movement of said part in one direction, placing said cord and contacts in elec- 40 trical engagement.

3. A plug for electric appliances including a plug body having contacts, an electric cord carried by a part of the plug body, said part embodying finger engaging portions to facilitate removal of the plug from the appliance, and being movable, when the body is in an operative position on an appliance, to urge the cord into engagement with and out of engagement from the plug contacts. 5

4. A plug for electric appliances including a plug body having contacts, an electric cord carried by a part of the plug body, said cord carrying part being movable, when the body is in an operative position on an appliance, to effect electrical engagement of the cord and contacts, and means in the plug to normally hold said cord carrying part in an outward position with respect to the plug body. 10

5. A plug for electric appliances including a body having contacts for engagement with an electric appliance, a part of said body being 20 equipped with a cord and movable for placing the cord in electrical engagement with said contacts, while the plug is in an operative position on an appliance, and spring elements projecting inwardly in said body and engaged with the movable part of the latter to normally urge said part out of electrical engagement with the body contacts. 25

6. A plug for electric appliances including a plug body having contacts for engagement with 30 an electric appliance, a part of said body being movable, electric terminals engaged with said movable part, and springs mounted in said plug body to electrically connect said terminals and contacts when the movable part of the plug body 35 is in one extreme position in the plug body, said springs normally urging the movable part out of electrical engagement with the body contacts.

EMANUEL B. BARNITZ. 40
